UNITED STATES PATENT OFFICE.

EDWARD G. MYERS AND JAMES W. CARRIER, OF LINCOLN, ILLINOIS.

LIQUID-FUEL BURNER.

1,115,722.

Specification of Letters Patent.

Patented Nov. 3, 1914.

Application filed February 13, 1914. Serial No. 818,516.

To all whom it may concern:

Be it known that we, EDWARD G. MYERS and JAMES W. CARRIER, citizens of the United States, residing at Lincoln, in the county of Logan and State of Illinois, have invented a new and useful Liquid-Fuel Burner, of which the following is a specification.

The present invention appertains to liquid fuel or hydrocarbon burners, and aims to provide a novel and improved burner for coal oil, petroleum, or other liquid fuel.

It is the object of the present invention to provide a burner adapted to be employed 15 in heating or cooking stoves, furnaces, boilers, and the like, or for divers other purposes, which shall be comparatively simple, durable, and inexpensive in its construction, as well as being practical and efficient in operation.

A further object of the present invention is to provide a burner embodying a combination retort and spreader in connection with a superheating coil and discharge 25 means directed toward the retort and spreader, whereby the spreader will direct the flames toward the superheating coil and whereby the spreader, in being heated, will vaporize or gasify the liquid fuel.

With the foregoing and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed without departing from the spirit of the invention.

The invention has been illustrated in its preferred embodiment in the accompanying drawing, wherein:—

Figure 1 is a perspective view of the improved burner, portions being broken away. 45 Fig. 2 is a sectional detail of the combination retort and spreader.

In carrying out the present invention, there is provided a suitable base 1, upon which is mounted a discharge pipe 2, by 50 means of clamps or other fastening means 3, one end of the pipe 2 having a cap 4 engaged thereon, and the other end of the said pipe having an elbow 5 attached thereto.

Attached to the elbow 5 is an upstanding 55 pipe 6, the same being formed into a horizontally disposed superheating coil 7, dis-

posed above and parallel with the base 1. An elbow 8 is attached to the free or upper end of the coil 7, it being noted that the lower end of the coil is attached to one end 60 of the discharge pipe 2.

A pipe 9 disposed radially of the coil 7 has one end attached to the elbow 8, and has its other or inner end attached to the combination retort and spreader. This retort 65 and spreader embodies a hollow disk-like body 11 having the coupling sockets 12 upon its top, and extending radially at diametrically opposite portions of the retort or body 11. The bottom of the retort and 70 spreader body 11 is flat and unencumbered and is disposed above the discharge pipe 2 centrally of or concentric with the upper convolution of the superheating coil 7.

The inner end of the pipe 9 is attached to 75 one of the coupling sockets 12 and a pipe 13 has one end attached to the other coupling socket 12, and is connected with a valve 14, which is in turn, connected with the liquid fuel supply pipe 15. The liquid fuel, such 80 as petroleum, crude oil, or the like, may be fed either by gravity, or under pressure, so is to pass through the valve 14, when the valve is open, to the retort or generator 11.

A copper or other rod 16 is disposed with 85 in the superheating coil 7, to assist in the heating of the vapor or gas passing therethrough, the discharge pipe 2 being provided with an upper aperture 17 coaxial with the superheating coil 7, and retort 11, 90 and disposed directly below the retort, to direct the flames against the bottom of the retort.

An upright draft tube or flue 18 has its lower end extending through an opening 19 95 formed in the base 1 below the vapor pipe 2, the flue 18 having diametrically opposite openings 20 through which the vapor tube 2 passes, in order that the outlet aperture 17 will be disposed centrally or axially of 100 the draft flue. The draft flue is also coaxial with the retort or gasifier 11, and its upper end terminates directly below the retort or gasifier, to provide an annular opening 105 between the flue and retort approximately in the plane of the upper convolution of the superheating coil.

In operation, when the valve 14 is opened, and the retort or gasifier 11 is primed in any suitable manner, the vapor or gas will pass 110 through the superheating coil and will be discharged from the pipe 2 through the

aperture 17, and up the draft tube 18, so that the flames when striking the spreader and retort 11 will continue to heat the same and will be directed radially from the 5 spreader, so as to heat the superheating coil. Thus, the retort 11 serves to gasify or vaporize the fuel, as well as spreading the flames toward the superheating coil, in order that the gas or vapor may be heated to 10 a high temperature, in order that a most effective combustion of the gas will result to produce a maximum heating effect with a minimum expenditure of fuel. It is to be noted that the body of the retort is dropped 15 below the axis of the pipes passing over the superheating coil, in order to best carry out the results desired.

The draft flue 18 is of advantage, inasmuch as a current of air will flow upwardly 20 therethrough from below the base 1, the air admixing with the discharged gas or vapor, to support combustion directly below the retort or gasifier. The base 1 is preferably of sufficient size, to fit over the grate of a, 25 fire box, to completely fit in the walls of the fire box, whereby air cannot pass upwardly around the sides of the base, but is constrained to pass upwardly through the flue 18. Thus, the tendency to cool the super- 30 heating coil, will be reduced to a minimum, and at the same time, the combustion of the gas will be more thorough.

The present burner may be placed in the fire box of a heating or cooking stove, or 35 may be employed for heating furnaces, boilers, or other purposes. If desired, the burners may be employed in multiples, for increasing the heating effect.

Having thus described the invention, what we claim as new is:—

1. In a liquid fuel burner, a horizontally disposed superheating coil, a combination retort and spreader, embodying a hollow disk-like body disposed centrally within the upper convolution of the said coil and having upper coupling sockets, the upper end of the said coil being connected to one socket, a liquid fuel supply pipe connected to the other socket, a discharge pipe connected to the lower end of the said coil and extending therebelow, the discharge pipe having an upper aperture directed toward the bottom of the retort and spreader.

2. In a liquid fuel burner, a base, a superheating coil disposed thereabove, a combination retort and spreader disposed centrally within the coil and connected to one end thereof, a draft flue communicating through the base and projecting toward the retort and spreader, a discharge pipe mounted upon the base and extending through the draft flue, one end of the discharge pipe being connected to the other end of the said coil, and the discharge pipe having an aperture within the flue directed toward the retort and spreader, and a liquid fuel supply pipe connected to the retort and spreader.

In testimony that we claim the foregoing as our own, we have hereto affixed our signatures in the presence of two witnesses.

EDWARD G. MYERS.
JAMES W. CARRIER.
